JACK M. KELSEY, OF BREA, CALIFORNIA.

CABLE-GUARD FOR TACKLE-BLOCKS.

1,379,868.

Specification of Letters Patent. Patented May 31, 1921.

Application filed May 24, 1920. Serial No. 383,703.

To all whom it may concern:

Be it known that I, JACK M. KELSEY, a citizen of the United States, residing at Brea, in the county of Orange and State of California, have invented a new and useful Cable-Guard for Tackle-Blocks, of which the following is a specification.

This invention relates to cable guards for tackle-blocks and is more particularly directed to guard which automatically adapt themselves to the varying angular disposition of the cable runs.

The object of the invention is to provide a cable guard for tackle-blocks, as a safety device designed to prevent accident to an operator by having his hands or clothing become caught between the block and cable runs or otherwise.

Another object is to provide a cable guard which automatically adjusts itself to varying angular and spreading movements of the cable runs and prevents the cables running off their respective cable sheaves, and which also prevents an upsetting of the block.

Another object is to provide a cable guard having a series of removable cable engaging elements capable of being assembled in varying numbers to coöperate with blocks having different numbers of cable sheaves and adapted for attachment to blocks of various sizes.

Various other objects and advantages will be more fully apparent from the following description of the accompanying drawings, which form a part of this disclosure, and which illustrate a preferred form of embodiment of the invention.

Of the drawings:

Figure 1 is a side elevation, partly in section, of a tackle-block embodying the features of my invention.

Fig. 2 is a partial end elevation.

Fig. 3 is a detail section on line x^3-x^3 of Fig. 1, and

Fig. 4 is an end elevation showing the device as shifted by a spreading of the cable runs.

In the drawings, the cable guard of the present invention is illustrated as applied to a "snatch block" as generally used as part of well drilling and operating equipment, and in such use the cable is rove around relatively separated crown pulleys at the top of the well derrick so that as the block is elevated toward the top of the derrick the runs of the cable adjacent the block

become more widely separated transversely and laterally. The present structure automatically adjusts itself to this separation of the runs of the cable and by engaging the cable runs above the pivoted center of the sheaves of the block prevents the block from upsetting in either direction.

While I have illustrated a three sheave block in the drawings, it will be understood that the cable guard herein disclosed may be applied to blocks having any number of sheaves and that any desired number of the cable housings or shoes as independent removable units may be assembled together for use on blocks of various sizes.

In the drawings, the frame of the block comprises two side plates 1, 2 and two intermediate spacing plates 3, 4, secured together at their opposite ends by transverse bolts 5, 6, the plates being maintained in spaced relation at each end by the hub portions 7, 8 of the upper and lower bails 9, 10, and by a spacing sleeve 11 as shown in Fig. 2, this being the general frame structure of standard tackle-blocks. The cable sheaves 12, 13, 14 are positioned between the plates and are journaled on a transverse rod 15 extending through aligned apertures therein.

Attached to the upper portions of each side plate 1, 2 I provide laterally extended bracket arms 16, 16 and 17, 17 each pair being relatively transversely aligned and extending outwardly. Carried by these bracket arms are transverse pivot rods 18, 18 each extended across and adjacent the faces of the cable sheaves and maintained against displacement by a head 20 and lock-nuts 21, 22. Each pivot rod is positioned between the faces of the cable sheaves and the adjacent runs 23 of the cable and form means for pivotally supporting the respective cable guards.

The guard elements for the cable runs are all of duplicate construction, each comprising a housing 24 of the U-shaped cross sectional contour, loosely pivoted on the respective pivot rod 18, the rod extending through transversely aligned pivot apertures 19 in the opposed limbs of the housing said apertures being enlarged to permit the housing to tilt transversely on the rod. Each housing is positioned on its pivot rod with its open side facing inwardly and the respective cable run passes upwardly in the cable-way between the rod and the back wall of the housing. A transverse retain-

ing rod 25 extends through alined apertures 26 in the opposed limbs of the several housings 24 and is positioned on the inside of the several cable runs 23 closing the upper portions of the open sides of the housings and engaging the inner surface of the cable runs to maintain the housings in position. The apertures 26 are enlarged so that each housing or shoe 24 may tilt transversely without binding on the rod 25 and the rod has a head 28 at one end and suitable lock-nuts 29, 30 on the opposite end, maintaining it against displacement. The lower edges of the cable housings 24 are flared outwardly so as not 15 to foul the cable during the various tilting and rocking movements of the housings.

In assembling the guard elements or housings on the block after the cable has been properly applied and with the block suspended as shown in Fig. 1, a proper number 20 of said housings, depending upon the number of cable sheaves in the block, are placed over the cable runs and the pivot rod 18 is threaded through the apertures in the 25 bracket arms and through the pivot apertures 19 of the several housings and the lock-nuts 21, 22 screwed on the rod to secure it against displacement. The retaining rod 25 is then threaded through the apertures 30 26 in said housings and the lock-nuts 29, 30 screwed thereon.

In use, the guard elements or cable housings will effectively prevent an operator from inserting his hand between the moving 35 cables and the cable sheaves and as the cable runs 23 spread apart to a greater tangential angle the housings will rock on their pivot rods, as indicated in dotted lines in Fig. 1. And when the cable runs 23 spread apart 40 transversely the housings will slide on the pivot rods and will tilt transversely to automatically accommodate themselves to the changing angular positions of the cable runs, as shown in Fig. 4, this tilting being 45 permitted by the enlargement of the apertures in the housings. The engagement of the cable housings or shoes with the cable above the center of the cable sheaves also prevents the block from upsetting and maintains the block in an approximate vertical 50 plane when not in use.

I claim:

1. A cable guard combining a tackle-block having a frame and a cable sheave, a 55 pivot rod carried by the frame and extended across the face of the sheave, a cable shoe loosely pivoted on said rod and adapted to embrace the sides and the outer surface of a cable rove around the sheave, and means 60 carried by the shoe adapted to engage the inner surface of the cable to maintain the shoe in position.

2. A cable guard combining a tackle-block having a frame and a cable sheave, a pivot 65 rod carried by the frame and extended across

the face of the sheave, and a cable shoe providing a U-shaped cable-way engaging the sides and the outer surface of a cable rove around the sheave and loosely pivoted on said rod, the shoe having means adapted to 70 engage the inner surface of the cable in said cable-way above the pivot rod.

3. A cable guard combining a tackle-block having a frame and a cable sheave, a pivot rod carried by said frame and extended 75 across the face of the sheave, a cable shoe providing a U-shaped cable-way engaging the sides and the outer surface of a cable rove around the sheave and loosely pivoted on the rod, and means engaging the opposed 80 limbs of the shoe and extending across the cable-way to engage the inner surface of the cable above the pivot rod.

4. A cable guard combining a tackle-block having a frame and a cable sheave, a 85 cable shoe U-shaped in cross section and positioned with its open side facing the sheave, said shoe having transversely alined apertures in its opposed limbs, a pivot rod carried by the frame and extending across the 90 face of the sheave and through said apertures and providing a cable-way between the rod and the back of the shoe, and means carried by the shoe, spaced from the pivot rod and adapted to engage a cable in the 95 cable-way to maintain the shoe in position.

5. A cable guard combining a tackle-block having a frame and a cable sheave, a pivot rod carried by the frame and extending across and positioned closely adjacent the 100 face of the cable sheave, a U-shaped cable housing loosely journaled on said rod and providing a cable-way between the rod and the back of the shoe, and means carried by the shoe and extended across the upper end 105 of the cable-way.

6. A cable guard combining a tackle-block having a frame and a plurality of cable sheaves, a pivot rod carried by the frame and extended across the faces of the sheaves, 110 a plurality of cable housings of U-shaped cross sectional contour pivoted on the rod and providing independent cable-ways, the pivot apertures being formed in the opposed limbs of each housing and enlarged 115 to permit an independent transverse tilting thereof, and a retaining rod extending through alined enlarged apertures in the opposed limbs of each housing and closing the upper ends of the cable-ways.

7. A cable guard combining a plurality of cable housings of U-shaped cross sectional contour providing independent cable-ways and having transversely alined pivot apertures in their opposed limbs, and other 125 transversely alined apertures in their opposed limbs spaced from the pivot apertures, a tackle-block having a frame and a plurality of cable sheaves, a pivot rod carried by the frame and extending across 130

the faces of the sheaves and through the pivot apertures of the cable housings, and a retaining rod extended through the other aligned apertures of the cable housings, both 5 rods being spaced from the back walls of the housings to form intermediate cable-ways, all the apertures being enlarged to permit an independent free transverse tilting of each cable housing.

10 8. A cable guard combining a tackle-block having a frame and a cable sheave, a cable rove around the sheave and having a tangentially extending run, a transverse pivot rod carried by the frame and positioned between 15 said cable run and the face of the sheave, a cable housing loosely pivoted on said rod and providing a U-shaped cable-way, the cable run passing between the pivot rod and the back wall of the housing, and 20 means closing the upper portion of the cable-way and engaging the cable run to maintain the housing in position.

9. A cable guard combining a tackle-block having a frame and a plurality of cable

sheaves, a transverse pivot rod carried by 25 the frame and extending across and adjacent the faces of the sheaves, a plurality of cable housings loosely pivoted on the rod, each housing being of U-shaped cross sectional contour and forming a cable-way 30 between the pivot rod and the back wall of the housing, and a retaining rod extending through the opposed limbs of each housing and closing the upper portions of the open sides of the housings.

10. A cable guard combining a tackle-block having a frame and a cable sheave, a pivot rod carried by the frame and extended across the face of the sheave, and a cable 40 engaging member pivoted on said rod and adapted to tilt transversely relative to the plane of the cable sheave.

Signed at Los Angeles, California, this 18th day of May 1920.

JACK M. KELSEY.
